UNITED STATES PATENT OFFICE.

NILS E. NORSTROM, OF CHICAGO, ILLINOIS, ASSIGNOR TO N. E. NORSTROM ELECTRIC MANUFACTURING COMPANY, OF CHICAGO, ILLINOIS, A CORPORATION OF ILLINOIS.

MASSAGE VIBRATOR.

Application filed June 22, 1922. Serial No. 570,103.

My invention relates to massage vibrators, and has for its object improvements in such devices.

In the accompanying drawings—

- 5 Fig. 1 is an elevation;
 Fig. 2 is a similar elevation with the exterior parts in section;
 Fig. 3 is an elevation of the interior parts in a direction opposite to that shown in
 10 Fig. 2;
 Fig. 4 is a section on line 4—4 of Fig. 2;
 Fig. 5 is a section on line 5—5 of Fig. 2;

Fig. 6 is a section on line 6—6 of Fig. 2.
 15 On the base 10 is a handle 11, and thru these extends a cord 12 made up of electric conductors 13 and 14 which extend to a winding 15 on a U-shaped core 16. The core 16 is supported on the upper face of
 20 the base 10 by posts 17 and bolts 18. Secured to the core 16 is a bail 19, and screwed into this is a supporting hook 20 provided with a collar or washer 21. The base 10 is provided with a flange 22, and resting on
 25 the base inside of this flange is the casing 23. This casing is held in place by the collar 21 on hook 20.

The magnetic core 16 is made up of laminae, as shown in Fig. 2, and these laminae are secured together by the bolts 18 which secure said core to the posts 17. The armature 24 is also made of laminae, each one of which has a notch near one end for the reception of a rod or bolt 25.

35 Secured to two of the posts 17 by screws 26 are plates 27, best seen in Figs. 5 and 6. These plates are shaped as shown in Fig. 5, and have therein a cut 28 so as to leave an overhanging spring 29, which spring is in
 40 fact a laminated spring.

A U-shaped spring 30 (Figs. 2, 3 and 6) has one leg 31 between the plate 27 and the posts 17, and is held in place by the screws 26. The other leg 32 of the spring 30 extends to the other side of the magnet. The rod 25 has one end secured to the spring 29 and the other end secured to the leg 32. These parts are so arranged that the rod 25 is normally inclined as shown in
 45 Figs. 2, 3 and 4. When rod 25 moves from inclined to horizontal position it deflects spring 29.

Between the spring 30 and the armature 24 is a rubber cushion 33. This cushion is
 50 preferably made of a piece of rubber tub-

ing which is split open on one side and spread out so that it takes the shape shown in Fig. 4. This cushion, which is under considerable initial compression, presses the rear ends of the laminae of the armature 60 against one pole of the core 16. At the other end this cushion forces the laminae of the armature against the rod 25. As this rod is normally in an inclined position, the armature as a whole has one corner only removed from the poles of the core. As the rod passes thru notches in the edges of the laminae, it serves to locate the armature with respect to the core. On the rod 25, between the leg 32 of spring 30 and the nearest lamina, is a spring 34 which serves to push the laminae of the armature toward the posts 65 70 75 80 85 90 95 100 105 110

From the foregoing it will be seen that the armature is composed of laminae which are not hinged in the ordinary meaning of that term, but are held in place by other devices. One of these is the cushion 33 which keeps one end of each lamina always in contact with one pole of the core by an upward push. The second of these other devices is the rod 25 which, by engaging notches in the laminae, locates laterally in one direction with respect to the core. The third is the spring 34 which presses the laminae toward posts 17 and thus serves to locate the armature in the other lateral direction. In this condition the laminae are clamped between rod 25 and cushion 33, and are guided by posts 17.

Located at about the center of the base 10 is a bridge 35, and mounted upon this bridge is a spring 36, which is below and parallel with the spring 30. At one end there is a piece of felt or other soft body 37 between springs 30 and 36. (Fig. 2). At the other end there is a thumb screw 38 which passes thru base 10 and spring 36 and is provided with a nut over the spring. These parts are so arranged that when screw 38 is turned, the spring 36 becomes a lever mounted upon bridge 35 as a fulcrum.

The spring 30 is fixed at the leg 31, the leg 32 being the free end of the spring. This spring is so stiff that the magnetic force of the magnet is not sufficient to attract the armature against the retracting force of the spring. But by turning screw 38 so as to force spring 36 against spring 30, the retractive force becomes the differ-

ence between the forces of the two springs. The amount of this difference is adjustable by turning the screw more or less.

Assuming the parts to be in the position shown in Figs. 2 and 4, an electrical impulse thru the winding 15 will cause an attraction of the armature. While being so attracted, the laminæ of the armature will move with respect to each other and will carry the rod 25 in a pivotal movement from its inclined position toward a horizontal one. In this movement of the rod, the spring 30 will be moved upward and the spring 36 will follow by reason of its initial tension which permits the armature to be moved. If the screw 38 should be adjusted so that the spring 36 will follow spring 30 until the armature is nearly but not quite in contact with the core, then the attracting movement will be stopped at this point because the attractive force of the magnet is not equal to the retractive force of the spring 30.

If the wires 13 and 14 are connected to an alternating current, then the armature will be attracted and retracted without the free end of the armature coming in contact with the core, and consequently without making any noise by metal striking on metal. As the fixed end of the armature is always in contact with the core and the free end always in contact with rod 25, there are no blows and consequently no noise at these points. The soft cushion 33 between the armature and spring 30, and the pad 37 between springs 30 and 36 also prevents metal contact at these points. In fact the device is designed to be noiseless in operation.

On the free end of the rod 25 is a head 40 which has an axial hole provided with a screw thread, and into this is screwed a stem 41 provided with a massaging head 42. In the case 23 at this point is a slotted hole 43 for the passage of the stem 41. When the magnet is operated by an alternating current, the head 42 is vibrated back and forth so as to produce a rubbing action when applied to the body.

What I claim is:

1. In a device of the class described, a core and winding therefor, an armature composed of relatively movable laminæ, and connections so arranged that upon an alternating current flowing thru said winding one corner of said armature will be moved to and from the core by the movement of the laminæ with respect to each other, the remaining three corners remaining substantially stationary while said one corner moves.

2. The combination with a magnet, of an armature composed of relatively movable laminæ not attached to each other or to the magnet, and spring devices arranged to hold

said laminæ in proper relationship to each other and to said magnet and to also provide a retractive force for said armature.

65

3. In a device of the class described, an armature composed of laminæ parallel with the plane of armature movement, each laminæ having a notch near one end, a pivotally movable rod located on the inner side of the armature and transversely to the laminæ thereof, and a cushion bearing against the outer face of the armature and serving to press the notched parts of the laminæ against said rod.

70

4. In a device of the class described, a laminated spring, an instrument-carrying rod having one end secured to said spring, and a magnetic device arranged to move said rod upon its secured end in a pivoted manner.

80

5. In a device of the class described, a spring, a rod having one end secured to said spring and pivotally movable by a deflection of said spring, and a magnet having an armature arranged to so move said rod and said rod serving to retract said armature by the action of said spring.

85

6. The combination with a magnet and a supporting frame therefor, of an armature composed of loose laminæ located between parts of the frame, a retractive device engaging the upper edges of the laminæ to move them from the magnet, a spring for operating said retractive device, and a cushion carried by said spring and acting against said laminæ to press them against said retractive device and one pole of said magnet.

90

7. The combination with a magnet and a supporting frame therefor, of an armature composed of loose laminæ, a retractive device engaging notches in the upper edges of the laminæ to move them from the magnet, and a cushion engaging the lower edges of the laminæ to hold them against the retractive device.

95

8. The combination with a magnet and a supporting frame therefor, of an armature composed of loose laminæ, a retractive device engaging notches in the upper edges of the laminæ, a cushion engaging the lower edges of the laminæ and serving to hold them against the retractive device, and a spring on the retractive device and serving to press the laminæ toward a part of the frame.

100

9. In a device of the class described, a magnet, an armature composed of loose laminæ parallel with the plane of the armature movement, a retractive device engaging notches in the upper edges of the laminæ, and a cushion engaging the lower edges of the laminæ and serving to press them against the retractive device.
